GOLF CLUB HANDLE

William Clyde Dishner, Jr., 623 Detroit St., Flint, Mich.

Filed Mar. 16, 1961, Ser. No. 64,348

Term of patent 14 years

(Cl. D34—5)

FIGURE 1 is a perspective view of my design for a golf club handle.

FIGURE 2 is a top plan view of my design for a golf club handle.

FIGURE 3 is a side elevation view of my design for a golf club handle.

FIGURE 4 is a front elevation view of my design for a golf club handle.

FIGURE 5 is a cross section view taken on line 5—5 of FIGURE 3 of my design for a golf club handle.

FIGURE 6 is a cross section view taken on line 6—6 of FIGURE 3 of my design for a golf club handle.

The broken line showing in FIG. 1 of part of a golf shaft is for purposes of illustration.

I claim:

The ornamental design for a golf club handle, as shown and described.
